UNITED STATES PATENT OFFICE.

EDWIN W. MCKINLEY AND EARL J. GRIGSBY, OF AKRON, OHIO.

TAIL-LAMP FOR MOTOR-VEHICLES.

1,238,419.

Specification of Letters Patent. Patented Aug. 28, 1917.

Application filed October 9, 1916. Serial No. 124,710.

To all whom it may concern:

Be it known that we, EDWIN W. MCKINLEY and EARL J. GRIGSBY, citizens of the United States, residing at Akron, in the county of Summit and State of Ohio, have invented certain new and useful Improvements in Tail-Lamps for Motor-Vehicles, of which the following is a specification, reference being had to the accompanying drawings.

This invention relates to an improved tail lamp for motor vehicles and has for its primary object to provide a device of this character, including means which is operable from the driver's seat, whereby another motorist in the rear of the vehicle may be made aware of the driver's intentions, and possibility of collision, thus obviated.

It is another and more particular object of the invention to provide a motor vehicle tail lamp including a casing having a glass or lens in its side wall, illuminating means for the interior of the casing, and a rotatable drum mounted within the casing and having panels therein, certain of which bear suitable indicia, one of said panels being colored red and normally disposed opposite the lens in the casing.

It is another important object of the invention to provide improved means for mounting the rotatable drum within the casing, whereby the same may be easily and quickly removed when desired, the casing for said drum having a hinged end wall also provided with a lens, the device as a whole being highly efficient and reliable in practical use and capable of manufacture at relatively small cost.

With the above and other objects in view, our invention consists in the novel features of construction, combination and arrangement of parts to be hereinafter more fully described, claimed and illustrated in the accompanying drawing, in which,

Figure 1 is a side elevation of a motor vehicle having our improved tail lamp applied thereto;

Fig. 2 is a vertical sectional view through the lamp;

Fig. 3 is a section taken on the line 3—3 of Fig. 1;

Fig. 4 is a perspective view of the rotatable drum removed from the lamp casing.

Referring in detail to the drawing, 5 designates the lamp casing which is substantially of cylindrical form and constructed

of sheet metal. This casing, however, is provided with a plain vertical front wall, indicated at 6, having suitable guides to receive an uncolored transparent glass or lens 7. 60 The casing 5 is provided at one end with a hinged wall or door 8, said door having a central lens or bull's eye 9, preferably colored red. At this end of the casing, the same is provided with an interior supporting 65 spider 10. The opposite end wall of the casing has a bearing 11 centrally fixed therein, said bearing being formed of copper or other good electrical conductor.

Within the casing 5, a sheet metal drum 12 is rotatably mounted, said drum being provided upon its ends with the axially projecting stub shafts or trunnions 13 and 14 respective. Each of these trunnions has a conical bearing terminal and the terminal 70 13' of the trunnion 13 is engaged in a conical seat provided in the bearing 11. The other terminal 14 of the drum is similarly mounted in one end of an adjustable screw 15 which is centrally threaded in the spider 80 10. The trunnion 13 is formed of a suitable non-conducting fiber for a purpose which will be presently stated. The bearing terminal 13' of this shaft is in the form of a 85 separate metallic cap.

The drum 12 has a plurality of elongated spaced openings 16 cut therein, five in number. Transparent sign or signal plates 17 are arranged over four of these openings and a red colored signal plate 18 is arranged 90 over the other opening. The plates 17 bear the words "Stop", "Right", "Left" and "Slow", respectively.

Upon the shaft or trunnion 13, a bevel gear 19 is fixed. A flexible shaft 20 extends 95 longitudinally beneath the vehicle body and a bevel gear 21 on the rear end of this shaft, which is suitably mounted in the wall of the casing 5, is in meshing engagement with the gear 19. A similar gear 22 is also fixed 100 upon the forward end of the flexible shaft and engages the bevel gear 23 on the lower end of a rod 24 rotatably mounted in suitable bearings fixed upon the steering post or column of the motor vehicle. The upper 105 end of this rotatable rod has a suitable handle 25 connected thereto, movable over an indicator plate or quadrant 26. The surface of this quadrant is suitably graduated and the lever 25 when moved to any one of the 110 positions indicated thereon, transfers rotation to the drum 12 through the medium

of the flexible shaft 20 to dispose the signal plate carried by said drum, corresponding to the indication on the graduated plate 26, opposite the transparent plate 7 in the wall 5 of the casing 5. Under normal conditions, or when the operator has no intention of turning or slowing up, the transparent red plate 18 on the drum is disposed opposite to the transparent plate 7 in the casing wall. 10 To the end wall of the drum to which the shaft 13 is fixed, an inwardly projecting tubular rod 27 is suitably secured and has a lamp socket on its inner end to receive the electric light bulb 28. One of the circuit 15 wires to said lamp is connected to the bearing 11, in which the conical bearing member 13' is engaged and a conducting wire 29 extends along the shaft 13 and through the pipe or tube 27 to one of the contacts 20 of the lamp socket. The other side of the circuit is closed through the casing 5, bearing frame 10, the wall of the drum 12, and sleeve 27, to the other socket contact. It will, of course, be understood that a push 25 button or other suitable switch is arranged in circuit for the lamp bulb 28.

The opposite end wall of the drum 12 is of skeletonized construction or formed with a plurality of spaced openings through 30 which the light rays are disseminated so that the lens 9 in the end of the casing 5 is illuminated.

From the foregoing description taken in connection with the accompanying drawing, the construction and manner of use of 35 the device will be apparent. By means of our improved tail lamp, the operator without removing his hands from the steering wheel, may quickly rotate the drum to the 40 desired position so as to expose to view, through the transparent plates 7, the proper signal carried by the drum and thus indicate to another motorist in the rear his intentions relative to the subsequent movement of the 45 vehicle. The possibility of collision, with consequent injury to the occupants may thus be avoided. It will, of course, be understood that if desired, the license tag or plate may be suspended from the bottom of the 50 casing, or arranged at one side thereof. The construction and arrangement of the several elements employed is quite simple and it will, therefore, be manifest that the device 55 may be constructed and applied to an ordinary motor vehicle at relatively small cost.

While we have shown and described the preferred construction and arrangement of the several parts, it is understood that the same are susceptible of considerable 60 modification and we therefore reserve the privilege of resorting to all such legitimate changes as may be fairly embodied within

the spirit and scope of the invention as claimed.

Having thus described this invention, what we claim is:—

1. A tail lamp for vehicles including a fixed casing, a rotatable drum in said casing carrying a plurality of transparent signal plates, a bearing fixed to one end wall of the casing constituting an electrical conductor and having a conical bearing seat, a trunnion of insulating material fixed to the corresponding end wall of the drum, a metal terminal on said trunnion having a conical portion for rotation on said seat, an electric light bulb within the drum, and electrical connections between said bulb, the metallic terminal of said trunnion, and said bearing. 80

2. A tail lamp for vehicles including a fixed casing having a transparent plate in the wall thereof, a bearing fixed to one end wall of the casing, a spider in the opposite end of said casing, an adjustable bearing mounted in said spider, a drum having trunnions on its opposite ends rotatably engaged in said bearings, said drum being provided with a plurality of spaced transparent signal plates, manually operable means for rotating the drum to its predetermined position, and an electric light lamp rotatable with the drum and disposed in coaxial relation therewith, the circuit for said lamp being closed through one of the bearings for 95 the drum. 90

3. A tail lamp for vehicles including a fixed casing having a transparent plate in the wall thereof, a bearing fixed to one end wall of the casing, a spider in the opposite end of said casing, an adjustable bearing mounted in said spider, a drum having trunnions on its opposite ends rotatably engaged in said bearings, said drum being provided with a plurality of spaced transparent signal plates, manually operable means for rotating the drum to its predetermined position, an electric light lamp rotatable with the drum and disposed in co-axial relation therewith, the circuit for said lamp being closed through one of the bearings for the drum, and a hinged door on one end of said casing provided with a colored lens, the corresponding end wall of the drum having openings therein, from which the rays of the lamp 110 bulb are admitted upon said lens. 100

In testimony whereof we hereunto affix our signatures in the presence of two witnesses.

EDWIN W. McKINLEY.
EARL J. GRIGSBY.
